T. & S. Hardgrove
No. 1,163. Design for a Trade Mark.
Patented Nov. 1, 1859.

Des 1163

Thomas Hargrove & Samuel Hargrove, of Richmond, Va.
Letters Patent No. 4463. Dated Nov. 1, 1850.

The schedule, referred to in these Letters Patent and making part of the same.

To all to whom these Presents shall come:

Be it known, that we Thos & Saml Hargrove of Richmond in the County of Henrico, and State of Virginia, have invented or produced a new and useful Design of Picture to be affixed to our wares and Manufactures, and that the following is a full, clear, and exact description of the same, reference being had to the accompanying print or picture.

Our invention or production consists in the ornamental design for a trade mark as shown by the accompanying representations.

What we claim and desire to secure by Letters Patent is the within described design of picture to be affixed to our wares and Manufactures and to be designated as the Peach brand.

Witnesses.

John Birchett.
